UNITED STATES PATENT OFFICE.

ALFRED S. BURNHAM, OF PARKERSBURG, IOWA.

SOFA-BED.

SPECIFICATION forming part of Letters Patent No. 278,870, dated June 5, 1883.

Application filed April 21, 1883. (No model.)

To all whom it may concern:

Be it known that I, ALFRED S. BURNHAM, a citizen of the United States, residing at Parkersburg, in the county of Butler and State 5 of Iowa, have invented certain new and useful Improvements in Extension Sofa-Beds; and I do declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 Figure 1 of the drawings is a front view of the sofa. Fig. 2 is a top view; and Fig. 3 is an end view.

This invention has relation to convertible 20 lounges or sofas; and it consists in the construction and novel arrangement of devices, as hereinafter set forth, and particularly pointed out in the appended claims.

In the accompanying drawings, illustrating 25 this invention, the letter A designates a sofa having below the seat B a recess or cavity to receive an extension, C, when the latter is in contracted position. The extension C is designed to form the body portion of a bed, whereof the seat B of the sofa may form the 30 head-rest. The extension C consists of parallel slats D running in the direction of the length of the sofa, and connected by jointed arms or strips e near each end. Each slat is supported upon legs F, and is braced in horizontal position by means of sliding bars g, which engage bearings h on the upper or lower surface of said slats. These bearings may be provided with anti-friction rollers, if thought desirable. The horizontal brace-bars g extend in the trans- 35 verse direction with relation to the length of the sofa, and they are of short length in order that they may all slide under the seat of the sofa when the extension is pushed into the recess or cavity thereof. A series of these 40 slides is arranged near each side of the extension, so that all the slats are firmly braced one to another in horizontal position.

The slat which is nearest to the sofa-frame is designed to be connected thereto by means

of sockets s and rods r, which project from the 50 back wall of the recess or cavity under the seat as far forward as the front of the sofa. When the extension is pulled out the last slat slides forward on the rods s. The slat at the other end of the extension is attached to the 55 front piece, L, to which the foot-board N, if one is employed, is hinged to fold inward and pass under the seat when the extension is pushed thereunder.

The slats are provided with springs P, 60 which may be connected by links z to extend the bearing for a mattress, which, when placed in position on the extension, will bring the bed-surface up about even with the seat of the sofa.

Having described this invention, what I 65 claim, and desire to secure by Letters Patent, is—

1. A sofa or lounge having a recess under the seat and a bed-bottom extension consisting of slats having legs and braced together by 70 short horizontal slide-bars engaging bearings of the slats, said bed-bottom being adapted to be contracted into the recess under the seat, substantially as specified.

2. A sofa or lounge recessed under the seat 75 and having an extension consisting of parallel leg-supported slats, connected by jointed arms or strips and braced by short slide-bars arranged in series on each side of the extension, substantially as specified.

3. The combination, with a sofa or lounge recessed under the seat, of a series of parallel leg-supported slats connected together by jointed arms and braced by sliding bars, the rods r, connecting the series of slats to the sofa-back, and the folding foot-board, substantially 85 as specified.

4. The combination, with the recessed sofa or lounge and its connecting-rods r, of the extension consisting of the leg-supported slats 90 and their connections, as specified.

In testimony whereof I affix my signature in presence of two witnesses.

ALFRED S. BURNHAM.
